UNITED STATES PATENT OFFICE.

RALPH NELSON DOBLE, OF BAYSIDE, NEW YORK, ASSIGNOR TO PNEUMATIC SCALE CORPORATION, LIMITED, OF NORFOLK DOWNS, MASSACHUSETTS, A CORPORATION OF MASSACHUSETTS.

PACKAGING MACHINE.

Application filed March 10, 1924. Serial No. 698,120.

This invention relates broadly to packaging materials, and more particularly relates to an improved method of and apparatus for packaging any commodity which it may be desired to pack in predetermined quantity whether of volume or weight in separate containers.

This invention more especially pertains to an improved method of and means for forming, filling and closing and, if desired, trimming and tagging a series of containers of limited volume and containing a predetermined quantity of the commodity to be packed.

For the purposes of disclosure merely, the invention is illustrated and described as embodied and adapted for the packaging of a selected material in a series of containers of predetermined volume, and as an exemplification of one employment of the invention it is here described as utilized for the purpose of packaging tea or the like in relatively small quantities in convenient individual containers, but it will be appreciated that the invention finds a wide field of utility for other purposes.

It is now quite common practice in the better hotels, restaurants and the like to serve individual portions of tea in small porous containers having a closing string tied thereto and a tag or the like on the string whereby the patron served may suspend the container in a pot or cup of hot water and make the tea of the strength desired.

The apparatus of the present invention is designed to manufacture, fill and tag these small containers in large numbers by a substantially continuous series of operations whereby quantity production may be inexpensively attained. It will be obvious, of course, that the field of utility of the invention for packaging other commodities, edible or otherwise, is by no means limited to the particular subject described hereinafter and illustrated in the drawings, nor to the employment of the particular kinds of packaging and closing material nor to the particular kind of tag or the like affixed thereto.

The principal objects and advantages which characterize this invention reside in the provision of an improved method of packaging commodities; the provision of an improved apparatus for packaging commodities and more particularly for simultaneously

measuring and packaging commodities; the provision of an improved method of and apparatus for constructing a container; the provision of an improved method of and apparatus for measuring a commodity, constructing a container and filling the container with such commodity; the provision of an improved method of and apparatus for constructing and filling a container and for applying a closing means thereto; the provision of an improved method of and apparatus for constructing and filling a container substantially simultaneously; the provision of an improved method of and apparatus for constructing and filling a container, in combination with means for conveying such container; the provision of an improved apparatus for forming and filling a container substantially simultaneously, in combination with means for grasping and conveying the container; the provision of an improved apparatus for closing a receptacle; the provision of an improved apparatus for applying a closure such as a string, wire or other filament to a filled container; and the provision of an improved apparatus for applying a tag or other object to a receptacle; the provision, in combination, of means for forming, closing and trimming said receptacle; and the provision, in combination, of means for forming, closing, and applying a tag or the like to a receptacle.

This invention is further characterized by the provision of apparatus for forming an improved form of container; the provision of an improved apparatus for manufacturing a complete container by substantially one continuous operation; the provision of an improved apparatus for forming a complete container from a single blank or piece of material; the provision of improved apparatus for forming a container from a single blank or piece of fabric, such as cloth or paper, by substantially one continuous operation; the provision of an improved apparatus for forming and filling a container substantially simultaneously; the provision of an improved apparatus including, in combination, means for forming a container from a single piece of material and means for automatically filling said container substantially simultaneously with its formation; the provision, in combination with means for forming a container characterized as above set forth, of

means for trimming the container, means for applying a closing means thereto; and the provision of means for forming and filling a container in combination with means 5 for trimming said container, means for applying a closing means to said container, and means for applying a tag or other object thereto, the provision of an improved method of applying a tag or other object to a container; and the provision of an improved mechanism for applying a tag or other object to the filament employed for closing the container.

This invention is still further characterized by the provision of an improved method of and apparatus for constructing a series of containers from a continuous web or strip of material; the provision of an improved method of and apparatus for manufacturing 10 containers from a single strip of fabric, cloth or paper and for applying closing means thereto; the provision of an improved method of and apparatus for packaging a commodity in a reticulated fabric or other porous container; the provision of an improved method 15 of and apparatus for applying a closing means to a container and for attaching means to said closing means for lifting said container; the provision of an improved method of and apparatus for measuring a commodity, forming a container to receive said commodity in a predetermined quantity, closing said container and for applying means for lifting the container, all by substantially a 20 continuous operation; the provision of an improved apparatus for forming a container from a single blank of material by the application of pressure at different points to said blank simultaneously; the provision of 25 an improved apparatus for forming a container from a single blank of material by the application of pressure in opposite directions at different points on said blank to form a container; the provision of improved 30 container forming apparatus characterized by the embodiment therein of filling apparatus; the provision of improved container forming apparatus characterized by the embodiment therein of means for measuring a 35 quantity of commodity and means for delivering said commodity to said container all substantially by a single continuous operation; and the provision of an improved method and apparatus of the character referred to which is rapid and economical in 40 operation, and facilitates the quantity production of filled containers without contact of the human hand therewith.

This invention is still further characterized by the provision of an improved apparatus including improved means for forming a container, means for filling said container, and means for applying a closing means to the container, all of said means being ar-

ranged to perform their respective functions 65 while the container is carried by a turn-table; the provision of an improved apparatus which includes means for forming a container, means for filling such container and means for conveying said container including a turn-table, 70 in combination with means for applying a closing means to the container; the provision of an improved apparatus which includes means of manufacturing a container and means for filling said container and means for simultaneously closing and grasping said container 75 for further operations; the provision of improved means for forming and filling a container, means for grasping and conveying said container, and means for applying a fastening 80 means to the container, said conveying means including a rotatable member; the provision, in combination, of improved means for filling a container, means for grasping said container and for conveying same for 85 further operations, said conveying means including a rotatable table; the provision of improved conveying means including object engaging means and a rotatable member for supporting same; the provision of an improved 90 conveying means which includes a rotatable member and object engaging means carried by the same, in combination with means for operating said object engaging means during the rotation of said rotatable member; and the provision, in combination with container 95 forming and filling and closing means, means for moving the container through a path adjacent to such means by a step by step movement.

This invention is still further more specifically characterized by the provision of improved tying apparatus; the provision of improved apparatus for applying a closing means to a container; the provision of improved means for applying a closing filament or the like to a container; the provision of an improved closure looping mechanism; the provision of an improved closure looping and tying mechanism; the provision of an improved object engaging means in combination 105 with means for applying a loop or loops of closing material to said object; the provision of looping mechanism in combination with an improved filament feeding and tensioning device; the provision of improved means for applying a tying material to a plurality of containers in succession, and the provision, in combination with said means, of means for successively disconnecting said several containers at the proper time.

The foregoing and other objects and advantages which appear or are pointed out as this description proceeds, are attained in a structural embodiment illustrated in the accompanying drawings; in which:

Figure 1 is a side elevation of the complete apparatus;

Figure 2 is a plan view on the line 2—2 and looking in direction of the arrows in Figure 1;

5 Figure 3 is a vertical transverse section taken on line 3—3 of Figure 1;

Figure 4 is a view of a detail of Figure 3 taken on line 4—4 of Figure 3;

Figure 5 is a vertical sectional elevation taken on line 5—5 of Figure 2;

10 Figure 6 is a plan view of the transfer table shown centrally in Figure 2;

Figure 7 is a sectional view taken on line 7—7 of Figure 6;

15 Figure 8 is an enlarged plan view of the bag-forming guide taken on the line 8—8 of Figure 7.

20 Figures 9 and 10 are, respectively, elevational and plan views of the bag-top trimming mechanism shown in elevation and in plan in Figures 1 and 2;

25 Figures 11 and 12 are elevational and plan views, respectively, (each of which is partly broken away) of the mechanism for tying up the neck of the bag or container;

Figure 13 is a view of part of such mechanism in another position it assumes in the operation of the machine;

Figure 14 is a rear elevational view of the tag feeding mechanism;

30 Figure 15 is a side elevational view of Figure 14 showing the means for feeding the twine into the eye of the tag;

Figures 16 and 17 are enlarged detailed views of portions of Figures 14 and 15; and

35 Figure 18 is a perspective view of the finished container.

Before proceeding to describe in detail the mechanisms herein illustrated for carrying into effect the desired objects, I will premise that I employ a rotating table or conveyor which carries the container from its initial state, filled, to the various instrumentalities which are to operate thereupon to form the finished object. I will further premise that

40 this conveyor is given a step by step movement corresponding with the initial association therewith of the container when thus formed and of the several operations to be performed thereupon. This conveyor there-

45 fore cooperates with the remaining mechanism of the machine, to permit the association therewith of the partly formed container and contents and then for the following operations to be performed upon this object: (a) of the trimming off of that portion of the container projecting above the conveyor; (b) the application of a plurality of loops of thread, wire or other filament about the neck suspended from the conveyor

50 and immediately therebelow for closing the container; (c) the association with the string so employed of a label or tag for each container formed, either for the purpose of identification or to be employed as carrying

65 means for the finished object; (d) the sever-

ing of the string so as to separate and disassociate the several objects when completed and to permit their discharge.

Referring more particularly to the drawings and first to Figures 1 to 3 inclusive, it 70 may be generally stated that this apparatus includes means generally designated A for feeding a continuous strip of fabric, preferably cloth of a texture and weave suitable for the purpose, such as coarse woven cotton material of the surgical gauze type; means for severing the strip into blanks, this means being designated generally as B; means for forming the blank into a pocket shape to form a container, this means being 75 generally designated C; means for measuring and delivering an increment of a predetermined quantity of some commodity and designated D; means for grasping and advancing the filled container generally designated 80 E; means for applying a fastening, such as twine to the neck of the container for closing the same and generally designated F'; means for applying a tag or other suitable object to the cord or twine and generally 85 designated G, and finally means generally designated H for severing the string which up until this point connects two or more of the containers together.

In the forming of the container a portion 95 thereof projects upwardly and to remove this portion a trimmer mechanism I is provided, and for delivering the completed, filled and tagged receptacle from the machine I provide a conveyor J.

100 The mechanisms just referred to are all co-ordinated and timed to operate in their proper relationship with respect to each other and to the container as it progresses through the machine and these mechanisms comprise, as 105 will hereinafter appear, certain specific elements which, of course, may be modified or varied in shape, construction and design for various purposes within the purview of the invention.

110 The mechanisms A to J, inclusive, are all preferably embodied in a single unit structure so as to render transportation of the apparatus convenient and these mechanisms are mounted on a frame composed of the horizontal side members 2 and 3 conveniently having a general shape in cross section similar to an I-beam as will best be seen in Figure 3. The side members 2 and 3 are connected by transverse end shelf members 4 and 4^a from the ends of which depend the supporting legs 4^b—4^b, preferably formed integrally therewith. Bolts 5^a or any other convenient fastening means extend through the depending ends of the side members 2 and 3 for securing 115 same to the shelf members.

120 The side members 2 and 3 serve to support, in bearings 29—29 a revoluble shaft 11 which may be termed the drive shaft, any suitable driving means, such as an electric motor, 130

(not shown) being connected to the projecting end of the shaft shown in Figure 3. This shaft serves to support a plurality of cams which will be described in detail hereinafter for actuating certain of the various mechanisms hereinbefore mentioned.

The shaft 11 serves to continuously drive a train of gears including the gear 5 mounted on the left hand projecting end of the shaft 10 11, as viewed in Figure 3, said gear 5 meshing with a gear 6, which is formed integrally with a reduction gear 7, the gears 6 and 7 being idling gears and mounted freely for rotation on the shaft 12. The gear 5 is pinned as at 15 5^b to the shaft 11 and the gears 6 and 7 are retained against longitudinal displacement in one direction by the bearing 6^a on the side member 3 and by a collar 7^a which is affixed to the outer end of the shaft 12. The gear 20 7 meshes with a gear 8 mounted on the shaft 13 and affixed to said shaft for imparting continuous rotation thereto, a gear 9, slightly larger than the gear 8, being formed integrally therewith and adapted to drive a 25 gear 14 mounted fixedly on the rotatable shaft 15.

The gears 5 and 6 are of substantially the same diameter, the gears 7 and 8 being also substantially of the same diameter, and the 30 gears 9 and 14 also being of the same diameter, so that the shafts 13 and 15 will be driven continuously at the same rate of speed as that of the shaft 11.

Upon reference to Figure 1 it will be observed that on each of the gears of the train just described I have applied an arrow and this serves to indicate the direction of rotation and it will be observed that the shaft 11 rotates clockwise and the shaft 13 in the same 40 direction, the shaft 15 rotating in a counter clockwise direction.

As an aid in making my invention clear to those skilled in the art it may be briefly stated that the shaft 11 while, of course, it is the 45 main actuating shaft of the machine, serves to directly operate only a portion of the elements, for instance, the shaft 12 being intermittently driven from the shaft 11 and serving to operate the mechanism E and the shaft 50 13 serving to operate the discharge conveyor J, the shaft 15 serving to operate the tagging mechanism G.

Briefly, the shaft 11 may be said to directly operate the trimming mechanism I, cutting 55 mechanism B, and operate certain elements of the tying mechanism F as will hereinafter appear. The shaft 11 serves to operate other elements which can be best explained as the description proceeds.

Below the planes of the shafts 11, 12 and 60 13 and located approximately midway between the shafts 11 and 12, I provide a fulcrum shaft 10, oscillatably mounted in bearings 10^a—10^a secured to the under sides of 65 the I-beams 2 and 3. This shaft is called a

fulcrum shaft because a number of levers are mounted on said shaft and operate upon and independently of same as a fulcrum. However, the shaft 10 oscillates at times with certain levers as will appear.

70

Referring now to the mechanism A for feeding the strip of cloth; mechanism B for severing; and mechanism C for forming the container; it will be observed upon examination of Figures 1, 2 and 3, that a platform 31 75 is mounted on the frame of the machine, supported by the frame F, which latter is in turn supported by one of the shelf portions 4 at the left hand end of the machine viewed from the aspect of Figure 1.

80

The frame F conveniently comprises a base 32, bolted or otherwise fixedly secured to the shelf 4, upstanding spaced sides 33 and 34 serving to support the platform 31, and also rearwardly extending arms 31^a, which carry 85 between them a roll 35 of the cloth or other material from which the blanks are cut and the containers are formed.

Integral with the frame and extending toward the center of the machine are divergent 90 arms 36 and 37 which form webs for integral connection of the vertical abutments 38 and 39 with the frame F. The walls 33 and 34 are connected at one end by a transverse wall 40, and thus, with the platform 31, form a substantially box like structure for rigid support 95 of the feeding, cutting, and forming mechanisms.

The vertical abutments 38 and 39 serve to rigidly support the posts 41 and 42, detachably secured to said abutments by means of bolts 43, 44, 45 and 46, and beyond the inner or discharge end of the platform 31.

100

The upper ends of the posts 41 and 42 project beyond and upon the surface of the platform 31, and are provided with bearings 47—47 and 48—48, yokes 49—49 extending over the bearings 48 as shown in Figures 1, 3 and 5.

105

A shaft 50 rotates in bearings 47 and carries a feed roller 51, and a shaft 52 rotates in the bearings 48 and carries a complementary feed roller 53. The roller 51 is circumferentially grooved at 50^a for a purpose which will presently appear. The bearings 47 are fixed, and the bearings 48 are slightly vertically movable against the tension of the springs 54—54, which abut the yokes 49, the tension of said springs being variable by the adjustment of set screws 55—55, and the bearings 110 115 being held by means of the guide rods 56—56. Obviously, this arrangement permits of the automatic variation of the tension existing between the peripheries of the rollers which are, in operation, in snug contact.

125

The feed rollers are simultaneously driven in relatively opposite directions by the provision of a gear 57 on the shaft 50 and a gear 58 on the shaft 52, said gears intermeshing 120 125 for the purpose specified.

130

A pinion 59 is fixed to the projecting end of the shaft 50 (Figure 5) and meshes with a pinion 60 revoluble on the bolt 46, which forms a bearing. The pinion 60 operates or 5 is integral with a sprocket wheel 61, over which a chain 62 is trained.

The strip of material from which the containers are formed is fed step by step to the forming mechanism, and this feeding is accomplished by imparting an intermittent rotary movement to the rollers 51 and 53, and further by the provision of a reciprocating tray (Figures 1 and 5) including the carriage 63 and the spaced arms 63^a—63^a which pass 10 between the rollers and are accommodated by the grooves in the roller 51, mounted on the frame F slightly above the plane of the platform 31. The arms 63^a are secured to the carriage 63 by screws 64.

20 For supporting and guiding the tray the carriage 63 is mounted upon and has a dovetail connection 65 with the platform 31 (Figure 5) and the arms 63^a are affixed to the carriage as pointed out, so that when the latter 25 is reciprocated, the tray arms 63^a are projected between the rollers 51 and 53 (see Figure 1). This arrangement permits of feeding of the cloth in the desired increments of the size required, these increments being substantially of the same length as that of the width of the strip, although this is not essential. As 30 the tray and rollers introduce the strip the former moves forward. The rollers then stop and the arms 63^a recede, the frictional contact 35 of the portions of the rollers which engage the cloth holding the cloth while the arms recede to a position ready for another feeding step.

The carriage 63 and tray 63^a are actuated 40 by the lever 66, fulcrumed by means of and connected fixedly to the transverse shaft 67, supported by frame F, the lever 66 being arranged inside of the frame F and connected by a link 68 to a lug on the bottom of the carriage (see Fig. 1).

The requisite motion for oscillating the shaft 67 is imparted thereto by the provision of an external lever 68^a fixed on the projecting end of shaft 67. A connecting rod 67^a 50 connects the lever 68^a to the upper end of lever 70, which is fulcrumed upon the shaft 10 and actuated by the cam 71 rotatable with the shaft 11. (See Figure 3.) A roller 70^a at the medial portion of the lever 70 engages 55 the cam 71. Thus, at the proper time, the carriage is reciprocated carrying the fabric and the latter is gripped by the rollers and thus fed in increments.

Intermittent motion is imparted to the 60 rollers through chain 62 by the provision of a sprocket 72 on the shaft 12, which latter is intermittently rotated by the Geneva gear mechanism 73, including the rotating pin member 74 on shaft 11, and the radially

slotted star wheel 75 on shaft 12. (Figures 65 2 and 4.)

Reference may now be had to the forming mechanism C, and blank severing mechanism. (See Figures 1, 2 and 3.)

When an increment of fabric is projected 70 from the rollers, it is received in the forming mechanism C, which comprises a die which includes a table or female portion 76 and a hollow plunger or male portion 77. These elements will be described in detail presently, it 75 being sufficient to mention that the table 76 is fixedly mounted below the plunger 77 and just forward of the rollers 51 and 53 in order to receive the strip of fabric as it is projected.

The strip is severed just forward of the rollers by the provision of a fixed knife edge carried by the rear edge of the table 76 and formed by transversely slotting the table and either attaching the knife edge or bending 80 down the edge of the table. The slot 79 thus formed receives the blade member 80, which latter is fulcrumed on a stud bolt 81 having a base 82 and a shank 83 which passes through an opening 84 (Figures 4 and 5) in the post 90 42. The blade has a lever 85 which projects to one side, as will be observed in Figures 2 and 3 and is connected by a universal joint 85^a to a rod 84^a which extends downwardly (Figures 3 and 4) and has a universal joint 95 connection 86 with the arm 87 of a bell crank 88, said lever being fulcrumed on the shaft 10. The other arm 87^a of the bell crank lever carries a roller 87^b which runs on the surface of the cam 87^c which latter is fixed upon and 100 is rotatable continuously with the shaft 11.

Wearing washers 83^a are interposed between the hub 80^a and the base 82 and any wear of said washers which does not require their renewal may be taken up by the nut 81^a 105 on the stub bolt 81, a helical expansion spring 84^b being interposed between the nut and the hub so that the knife blade will always move along the knife edge 78 when in operation. The universal joints 85^a and 86 allow for such 110 adjustment of the tension of the spring 84^b or any other lateral displacement of the blade in operation.

The forming mechanism hereinbefore referred to and including as its major element 115 the table 76 and the plunger 77 further includes a yoke 77^a which extends transversely and is fixedly connected to the upper ends of the guide and operating rods 77^b—77^b, the yoke 77^a rigidly supporting the plunger 77 120 which is provided with a hopper or funnel portion 90 disposed immediately below the measuring mechanism D. The plunger, as best shown in Figure 2, is substantially diamond shaped and the opening in the yoke 77^a in which said plunger is fixed is substantially of the same shape, so that the plunger can not turn in the yoke. 125

The guide rods 77^b are vertically reciprocated in supporting bearings 91 which latter are provided with base portions 91^a bolted to the posts 41 and 42 and the table 76 rests on the upper ends of said bearings 91 and may be secured thereto in any desirable manner.

The table 76 is provided with an opening 92 which is somewhat elongated and has its longest axis transverse to the longitudinal axis of the machine, inwardly directed tongues 93 being arranged at opposite ends of the opening and provided with notches 95 so that when the plunger is moved downwardly it passes through the opening 92 but instead of the opening being of the same shape as the plunger the shaping and forming is done by engagement of two corners or edges of the plunger with the notches 95 and the other edges of the plunger with the longitudinal edges of the opening 92. The recesses 96 afford room for the surplus fabric during the formation of the container, allowing the corners of the blank to project outwardly while the sides thereof are drawn upwardly, so that as the gripping mechanism closes, the corners of the blank are forced over the sides which as the bag is formed are embraced therebetween, giving an even grip about the blank and forming a symmetrical bag. This structure is more clearly shown in detail in Figures 7 and 8.

The plunger is moved downwardly through the table 76 by the provision of a pair of levers 94—94 fixedly secured to the shaft 10, the rear ends of said levers being pivotally connected at 95 to the lower ends of each of the rods 77^b. The cam 27 on shaft 11 operating the lever 27^a fixed on shaft 10 serves to actuate said shaft 10.

Each time the plunger descends it actuates the measuring mechanism D which includes the cup 96', to cause a quantity of the commodity to be deposited in said cup and when the plunger is depressed the spring pressed rod 97 is actuated by the yoke 77^a to simultaneously tilt the cup and thus deposit its contents in the hopper 90 so that the bag formed by the plunger and the table 76 is filled and formed at substantially the same time and with a single motion. When the plunger returns to its upper position it returns the cup to normal and the latter is filled again from a suitable container 98. The container 98, cup 96, and spring-pressed rod 97 are all mounted on a standard 98^a secured at 99 to the main frame of the machine.

The proper quantity of the commodity is permitted to flow into the cup 96 from the container by the provision of an electrically operated gate 96^a, operated at the proper instant and opened for the proper length of time by the provision of a commutating device such as the switch comprising the insulated drum 98^b on the shaft 18, contact plate 98^c and spring terminals 98^d on said drum.

When the plunger descends it will be readily appreciated that the presence of a blank of fabric over the opening 92 in the path of movement of the plunger will result in the fabric being forced through the opening 92, the outer edges of the blank being contracted to form the mouth of the container. It is in this position, that is, the position of partial formation, in which the container is in effect grasped between the plunger and the opening in the table, that the same receives the commodity to the desired amount as explained.

In order to grasp the container, contract its upper end to form a neck for closing same and for conveying the container to the point at which the surplus fabric is trimmed and to the other points at which the container is tied and tagged I provide a grasping and conveying mechanism which may best be seen from inspection of Figures 2, 6 and 7.

For supporting the conveying mechanism hereinbefore generally designated E, I provide a supporting standard 100 secured at 101 to the shelf portion 4^a of the base frame of the machine and extending rearwardly and laterally as at 102 to a point which is substantially at the center of or on the vertical axis of the machine. The standard 100 is provided, on the laterally extended portion 102, with a pedestal 103 having a vertical bore for rotatably receiving the vertical shaft 104.

On the lower end of the shaft 104 is mounted a bevel gear 105 which is adapted to mesh with a bevel pinion 106 fixedly mounted upon and rotatable with the intermittently operated shaft 12.

The upper end of the pedestal 103 receives a collar 107 provided with a cam portion 108, said cam and its collar being stationarily mounted on the upper end of the pedestal and secured in proper position thereon by the set screws 109.

The shaft 104 extends beyond the upper end of the pedestal and beyond said cam to receive a disc or wheel 110, the disc having a collar 111 secured concentrically on the under surface thereof and adapted to receive the upper end of the shaft 104 (Figure 7) and secured to the disc by the machine screws 111^a. The collar 111 encircles the shaft 104 and set screws 110^a extend through the collar and abut said shaft and thereby adjustably but firmly secure the turntable or disc 110 in its proper position with respect to the shaft 104.

The turntable 110 carries a plurality of gripping and holding devices and as these are substantially identical I will describe but one of them.

With reference to Figures 6 and 7 the gripping and holding device comprises a relatively fixed jaw 112 secured by the rivets 113 directly to the under side of the wheel or turntable 110 and projecting in a fixed plane radially from said turntable. The jaw member 112

is provided with a notch 114 having divergent sides and forming a tongue 115, the tongue 115 being in a lower plane than that of the jaw 112 by offsetting the jaw as at 116.

5 The movable jaw 117 of the device projects from the turntable and includes a notch 118 complementary and opposed to the notch 114, the jaw member 117 underlying the jaw member 112 but being offset at 119, so that the 10 tongue 120 of said jaw member will overlie the tongue 115 of the stationary jaw member. The reason for this arrangement is to prevent twisting of the container or the jaws or otherwise canting the container or distorting same 15 or the jaws when grasped, the arrangement distributing the pressure and thereby preventing the occurrence of any such defect. The movable jaw member 117 is fulcrumed on a pin 121, which may be a screw as shown in Figure 7, which projects downwardly from the under surface of the turntable, and said jaw is provided with an angularly disposed arm portion 122 which carries a roller 123 adapted to ride upon the peripheral surface of the 20 collar 107 and cam 108.

The movable jaw 117 is further provided with a downwardly bent portion 124 to which a contractile spring is attached, the opposite end of said spring being affixed at 126 to the 25 turntable. An inspection of Figures 6 and 7 will make it clear that the spring 125 tends to close the jaws and that these jaws are opened by the cam 108 so that the action of the 30 jaws will be relatively rapid, at least when closing. It will be observed that the jaws when open present an opening which is substantially of the same area and shape as that of the plunger 77. A ring 127 is secured by 35 rivets 128 or the like to the turntable 110 adjacent the periphery thereof and underlies the 40 jaw members 112 and 117 so as to strengthen the jaw members near their outer ends, prevent vibration and also to cause said members to move relatively in snug relationship.

45 When the turntable with the gripping and conveying devices is installed on the machine the periphery of the turntable 110 is disposed relatively close to the front edge of the table 76, as may be seen in Figure 7, so that the jaws in their path of travel will pass immediately beneath and close to the table 76.

The turntable is so actuated and the cam 108 is so positioned that from a predetermined point up until the jaws just begin to move out from under the table 76, these jaws are open so that as the plunger descends it not only forms the container as previously explained, but disposes such container within 55 the jaws of the gripping devices which are then open. The rotative movement of the turntable continues and just prior to the complete withdrawal of the plunger from the table 76 and the container, the rollers 123 leave the cam 108 and the jaws are then auto-

5 matically closed to grasp and contract the upper end of the container and form a neck therein. By reference to Figs. 6, 7 and 8 it will be observed that the opening 92 in the table 76 is of a particular construction and 70 shape and that the substantially diamond shaped opening formed by the cooperating notches 114, 118 of the grippers 112, 117, when in an open position, is located immediately below the supporting table 76 and the opening 92 therein. The size of the opening 92 is such that the side walls of the notches 114, 118 of the grippers, and which form the diamond shaped opening, are located beneath the recesses 96 forming a part of the opening 80 85 92. The particular shaped opening 92 in the table 76 and the gripping jaws located immediately below the same cooperate to form the bag in a novel and highly useful manner which may be briefly described as follows. After the individual blank of gauze has been 90 laid over the opening 92 upon the table 76 and has been cut off as previously described from the supply roll of gauze, the plunger 77 descends engaging the central portion of the 95 gauze blank and causing the central portion to be forced down through the center of the opening 92 in the table 76. The four recesses 96 shape the gauze blank into a partially 100 formed bag with four definite corner sections or folds in the mouth portion of the bag, one extending into each of the recesses 96. In the bag, in its partially formed condition as thus far described, there are four outwardly 105 extending folds, one at each of the four corners of the bag. Then as the plunger 77 continues to move the partially formed bag downwardly, each outwardly extended corner portion of the bag, which has been formed by a recess 96, is brought into contact with and 110 engaged by one of the side walls of the notches 114 and 118 of the clamping jaws located immediately below the table 76, and which form the diamond shaped opening 115 above referred to, and as a result of the continued downward movement of the plunger 77 the side walls of the notches 114, 118 operate to bunch each outwardly 120 extending corner portion of the partially formed bag and to gradually contract the neck portion of the bag so that in the partially formed condition in which the bag exists after the plunger has completed its downward movement and before the clamping jaws 112, 117 have closed, the mouth of the bag 125 comprises a flaring mouth portion in which the material is arranged in four definite bunches, each bunch comprising a relatively large number of individual folds of a more or less non-uniform character, and the adjacent bunches are connected by substantially unfolded portions of the mouth of the bag. Such substantially unfolded portions are formed by the inwardly extending tongues 93 of the opening 92 in the table 76 and by 130

the longitudinal sides of the opening 92. The next step in the operation of the formation of the bag comprises the filling of the bag and the withdrawal of the plunger 77, after which 5 the gripping jaws 112, 117 are closed, contracting the neck portion of the bag, drawing together the four definite corner bunches, and forming a compact bunched mass at the mouth portion of the bag. In the completed bag 10 formed as described the surplus material is gathered in four definite bunches with the individual folds comprising each bunch of a more or less non-uniform character and with the portions of the bag between the bunched 15 corners in a substantially unfolded condition.

The present method of bag formation lends itself particularly to the rapid and positive formation of the contracted neck portion of 20 the bag, and as a result of the direction of the surplus material at each corner of the bag into the outwardly extended corner folds by the recesses 96 in the plate and the subsequent bunching up of each corner fold into a compact 25 mass or bunch of non-uniform folds, it has been found that a minimum tendency exists for the gauze blanks to become clogged in the operating parts of the machine and as a result each bag is formed in a positive and efficient 30 manner.

The next step is to remove the surplus fabric of the container which projects above the jaws and which is naturally quite irregular and must be trimmed off to make a neat looking 35 package and this trimming mechanism will now be described in detail.

The trimming mechanism, generally designated I, and shown in enlarged detail in Figures 9 and 10, is conveniently situated at a 40 point between the forming mechanism and the bag tying mechanism and the actual cutting device of said trimming mechanism is located at a point immediately adjacent to and above a stationary position of one of the containers 45 which the latter assumes in progress around the circle defined by the turntable. For instance, after the bag is grasped and leaves the forming mechanism due to an increment of movement applied to the turntable it will 50 assume a position about half way between the forming mechanism and the trimmer as shown in Figure 2. Here it remains until the next increment of motion is applied to the turntable whereupon the container is moved to a 55 point immediately beneath the cutting element of the trimmer and so on throughout its path of travel through the machine. Therefore, this trimming mechanism is arranged in a position so as to trim the bag or container 60 while stationary.

The trimming mechanism as seen in Figures 1, 2, 9 and 10, comprises shears 129 including the fixed blade 130 and the movable blade 131. The movable blade is provided 65 with a hub 132 fulcrumed on a bolt 133 carried

by the horizontal portion 134 of a vertical standard 135 which has its base fixedly secured to the side member 3. The bolt 133 supports a compression spring 136, the tension of which is adjustable by the provision 70 of a nut 137 on the bolt 133. A lever 138 extends from the hub 132 and is pivotally connected with a link 139, which latter has a universal joint connection 140 with one arm 141 of a bell crank lever 142, which latter is 75 mounted on a fulcrum 143 carried by the inwardly extending portion 144 of a standard of support 145, said standard being secured to the side member 3.

The other arm 146 of the bell crank lever 80 is connected by a link 147 to the free end of an actuating lever 148 which is mounted upon the shaft 10. The lever 148 has a roller 148^a on the upper edge near the medial portion thereof and this roller is adapted to run upon 85 the periphery of a cam 21 which latter is fixedly secured to and rotates continuously with the shaft 11. The arrangement of the levers of this mechanism as shown places the cam 21 a sufficient distance toward the center 90 of the machine to allow for the position occupied by the cam 20 which performs the function which will presently appear.

The position of the shears 129 is such that they are disposed horizontally immediately 95 above the path of travel of the jaws which grasp the container so that the excess material of the container which projects above the gripping jaws will, upon an increment of movement of the turntable, be introduced into 100 the throat of the shears, and then the cam 21 in its proper time depresses the lever 148 and actuates the shears to sever the excess material.

After the container, gripped by the jaws 105 117 and 112 has been trimmed in the manner just described, an additional increment of movement is imparted to the turntable, which movement brings the container to a point designated M in Figure 2 and also indicated in the same manner in Figure 12.

When the container reaches the point designated M the bag tying mechanism F functions, this mechanism comprising the elements hereinafter more particularly described. 115

Referring now to Figures 1, 2, 11 and 12 and especially Figures 11 and 12 in which the detail parts are shown enlarged, I provide a double cam wheel 20, the cam parts thereof 120 being the laterally projecting rollers 20^a and 20^b. The rollers 20^a and 20^b are carried by a diametrically arranged arm 21^a which is secured to the wheel or disc 20 by the machine screws 22^a. 125

The rollers 20^a engage in the radial slots 149 of the star wheel 150 so that the cam wheel 20 and said star wheel form the essential parts of a so-called Geneva gear mechanism. This Geneva gear mechanism intermittently 130

operates the tying mechanism F' as will appear later.

The star wheel 150 is loosely mounted for rotation on the shaft 12 and is affixed to a gear wheel 151 which latter is in meshing engagement with a pinion 152 mounted on a hub 153 the latter being freely rotatable on the shaft 13. The hub 153, on its inner end is provided with a socket for receiving the shank 154 of a bevel pinion 155, the machine screws 155^a serving to fixedly secure the bevel pinion 155 on said hub 153.

A vertical standard 156 is bolted or otherwise secured at 157 to the top of the side member 3 and is provided with lugs 158—158 in which a revoluble vertical shaft 159 is journaled. The shaft 159 is supported by the standard 156 at a point some distance inwardly from the frame member 3 and is prevented from longitudinal motion in its bearings by the gear wheel 160 secured fixedly to the projecting upper end of said shaft and abutting the uppermost lug 158 and by means of the bevel pinion 161 fixed to the lower projecting end of the shaft 159 and abutting the lowermost lug 158. The pinion 161 is in meshing engagement with the pinion 155.

The standard 156 is provided at its upper end with a rearwardly and outwardly projecting arm 162 formed with a journal or bearing 163 for a revoluble shaft 164. The shaft 164 has a pinion 165 fixedly attached to and meshing with the gear 160 and resting on the top of the bearing 163 and a collar 166 is integral with or fixedly secured to the lower end of the shaft 164. The collar 166 has attached thereto by screws 167, the looping device which includes a horizontal radial arm 168 and a depending arm 169, the lower end of which is bent outwardly as at 170. The tying device is in effect a crank on the shaft 164 and engages with the string, as will hereinafter appear, to loop the same for application to the bag or other container for purposes of closing the mouth of the container. The shaft 164 is provided with an axial bore 171 through which the string or twine 172 is passed.

The rotation of the shaft 11 is imparted intermittently to the star wheel 150, thence by the gears 151 and 152 and pinions 155 and 161 to the shafts 159 and 164, whereby a plurality of revolutions are imparted to the shaft 164 intermittently. In other words, the shaft 164 is rotated only during the engagement of one or the other of the rollers 20^a or 20^b with the star wheel 150 during revolution of the shaft 11.

As the loop is formed by the revolutions which the arm 169 makes and as this arm is disposed to one side of the path of movement of the container, it is necessary that the loop thus formed be transposed to a position where it may be applied to the container. This feature of my invention I believe to be most

useful in view of the fact, among other things, that the loop is first made and then applied to the container and those devices of the prior art known to me usually apply the twine or other securing means directly to the container. The advantage of the present invention is that it permits, among other things, an increase of speed or rate of production, and provides for the automatic tightening of the loop around the neck of the container. 70 75

In order to receive the loop formed by the arm 169 and to apply this loop to the container I provide a cage-like element generally designated 173 carried by a horizontal arm 174 fixedly secured to and oscillatable in a horizontal plane by the provision of a vertical shaft 175, this shaft also being capable of vertical displacement and carrying the cage with it for a purpose which will presently appear. 80 85

A sleeve 176 surrounds the shaft 175, and said sleeve is revolvably mounted in a vertical bearing 177, said bearing being supported rigidly from the standard 156 or from any other convenient fixed point on the machine. 90

The cage is so supported by the arm 174 that in one of its positions, for instance, that shown in Figures 2 and 12, said cage is located directly beneath that one of the gripping elements which hold the container when stationary, and said cage is adapted in another position to be disposed axially below the shaft 164. 95

In the latter position mentioned the cage receives a loop of twine from the element 169 100 and in the other position applies this loop to a container.

The upper end of the sleeve projects beyond the upper end of the bearing 177 as at 177^a and supports the hub 174^a of the arm 174. 105 On the enlarged portion 177^a, forming the extension of the sleeve, is provided a cam 178 which performs a function which will appear as this description proceeds.

The sleeve is prevented against longitudinal movement by the provision of a collar 179 secured by a set screw 179^a to said sleeve, said collar abutting the lower end of the bearing 177. 110

The sleeve is oscillated in its bearing 177 115 by a mechanism which will be described presently and in order that the shaft 175 may move vertically relatively to the sleeve and yet rotate with the sleeve, a slot 180 is provided in the shaft and a transverse pin 180^a 120 carried by the sleeve extends through said slot.

The sleeve is rotated through an arc of approximately 80 degrees for shifting the arm 174 by the provision of the following 125 elements: A lug 181 on the collar 179 has a universal joint connection 181^a to a link 182, which latter has a universal joint connection 183 with a lever or rocker arm 184, loosely fulcrumed on the shaft 12. Rocking motion 130

is imparted to the rocker arm 184 by the provision of a reciprocating bar 185 pivotally connected at 186 to approximately the medial portion of the rocker arm 184, the rear end 5 of the bar 185 having a bifurcated portion to form a yoke 187 which embraces the shaft 11 and is guided thereon. A cam 23 on the shaft 11, provided with two high points 23^a lies parallel to and adjacent the bar 185, and 10 the periphery of said cam is adapted to engage a roller 188, mounted upon the medial portion of the bar 185, so that as the cam rotates, said bar is reciprocated, and thus rocks the arm 184. It will be obvious that 15 when the arm 184 is thus moved the link 182 will impart a partial rotation to the sleeve 186 and thus shift the cage carrying arm 174.

As will be seen from an inspection of Figure 12, the cam moves the arm 174 against the tension of a helical spring 189 having one end fixedly secured at 190 to the shelf 4^a and the other end affixed by a pin 191 to said sleeve 176.

As previously pointed out the pin 180^a in the slot 180 causes the movement of the sleeve 176 to be imparted to the shaft 175 to accomplish partial rotation of the latter, and to elevate and depress the shaft 175 I provide a mechanism embodying the following elements:

A lever 192 fulcrumed on the shaft 10 the longer arm of said lever being bifurcated to form a yoke 193 which embraces the shaft 175, 35 a collar 194 being carried between antifriction bearings 195—195 on the shaft 175, and the yoke being connected by links 196 to said collar. An expansion spring 197 surrounds the shaft 175 and is interposed between the 40 lower end of the sleeve 176 and one of the ball bearings 195, said spring tending to force the shaft 175 to its lowermost position.

The shorter arm of the lever 192 extends rearwardly below the cam 22 and carries a 45 roller 192^a which underlies the cam 22 which is affixed to the shaft 11 and is continuously rotated thereby. The cam 12 has its periphery in engagement with the roller 192^a and thus when the high point of the cam engages 50 said roller the forward end of the lever is raised thus elevating the shaft 175, arm 174 and the cage.

The cage itself includes a circular series of vertical posts or pins 173^a, the upper ends 55 of which extend through complementary notches in the inner periphery of a hub 174^a said posts 173^a being fixedly carried by the arm 174. It will be observed from Figure 12 that the annulus 174^a is supported upon a 60 spider frame 198 by vertically extending posts 199 and the spider 198 is vertically displaceable with the annulus relative to the arm 174 by the provision of a supporting column 198^a which operates in a bearing in

the arm 174. The lower end of said column 65 is pivotally connected to one arm of a lever 200 pivoted at 201 on the bottom of the arm 174. The other end of the lever 200 carries a roller 202 adapted, as will hereinafter appear, to contact with the cam 178 carried 70 by the sleeve 175. In operation of the machine the tying device actually functions when the turntable is in motion, that is, while one container is being moved into position to be tied, the cam 23 is positioned so that one 75 of its low points is in position to permit the cage to be presented to the tying crank 169, for receiving the loop. The arrangement of the cams 23 and 21^a and the Geneva star wheel 150 is such that the cam 23 first permits 80 the cage to move from the position shown in Figure 12 to a position immediately beneath the shaft 164, this movement being accomplished by the spring 189. When the cage has moved to the position mentioned, as best shown 85 in Figure 13, one of the pins 20^a or 20^b impart movement to the star wheel, which in turn, through the pinion 152, bevel gears 155 and 161 and gears 160 and 165 imparts one 90 revolution to the looping arm 169 thus throwing a loop of string or twine around the upper projecting ends of the pins 173^a, a clip 174^b being provided on the annulus 174^a for catching and holding, or at least placing a tension on a portion of the twine so that when 95 the cam 23 again comes around and swings the cage back to the position shown in Figure 12 immediately beneath a container which has in the meantime arrived at the point, the movement of the cage will not unravel the loop.

After this motion has been accomplished the cam 22 serves to depress the lever 192 at its rear end and thus elevate the shaft 175 which in turn elevates the cage 173 to encompass the container but not to come in contact with the gripping devices on the turntable. As the cage moves upwardly and just as it reaches the end of its upward path of movement the roller 202 on the lever 200 engages 110 the cam 178 and thereby lifts the annulus 174 with respect to the pins 173^a thus disengaging the loop of twine from said pins and depositing such loop around the neck of the container below the gripping devices, this being 115 accomplished by virtue of the fact that the twine is continuous up to a certain point and that one end being fixed on the spool of twine R and held by the clip 174^b and the other end of the twine extending over to the preceding container. The foregoing operation with respect to the formation of the loop is again repeated to place a second loop on the cage and to transfer it to the container before the turntable moves. The second loop is 120 thrown by the second high point on the cam 23^a. The movement of the container by a further turning of the turntable causes the 125

looped twine to contract about the neck of the container in which position it is held for further operations to be described.

5 A finger 170^a fixedly mounted on the arm 174 serves to engage a part of the string or twine and cooperate with the clip 174^b during the tying operation.

In order to maintain the twine 172 taut at certain intervals and to advance or feed the 10 twine I provide a mechanism best shown in Figures 1 and 2 and including a standard 172^a mounted on a shelf 4^a. At the upper end of the standard a lever 172^b is fulcrumed, the inner end of said lever having a pulley 172^c 15 thereon arranged with its periphery above the axis of the opening 171 in the shaft 164. A clip 172^d is secured to the lever 172^b and is provided with apertures through one of which the upwardly extending stretch of 20 twine passes and through the other of which the downwardly extending stretch of twine passes toward the looping device.

Below the lever 172^b at a point approximately half the distance up on the standard 25 172^a I provide a floating lever 305, the inner end of said lever 305 having a series of pulleys 306 over which the twine is trained, the outer end of the lever 305 having a friction device 307 for feeding the twine from the 30 spool R. The twine is trained through a bracket 308 carried by the lever 305 ahead of the friction device for an obvious purpose.

The outer end of the lever 172^b is pivotally connected to a rod 309 which extends 35 downwardly past the lever 305 and through the lug 310 formed on one of the actuating levers 311. The lower end of the rod 309 is provided with an abutment means, such as as the nut 312, for preventing the rod 309 from 40 lifting out of the lug 310 and also for imparting motion to said rod 309 upon a predetermined motion of the lever 311. The rod 309 is connected to the lever 305 approximately 45 at the medial portion thereof by the provision of a helical contractile spring 313 so that the tendency of said spring is to move the outer end of the lever 172^b toward the lever 305.

A second operating lever 314 is provided; 50 the levers 311 and 314 being pivotally mounted at 315 on an inclined post 316 supported by the shelf 4^a. The levers 311 and 314 are each provided with rollers 316 and 317 which ride upon the periphery of a cam 55 318 fixed upon and rotatable with the shaft 15, the cam having a cutaway portion 318^a for permitting downward displacement of both of the levers. The levers 311 and 314 are maintained in contact with the cam and 60 moved in one direction by the helical springs 319 and 320, respectively. It will be observed that the lever 314 is shorter than the lever 311 so that they will operate in succession for a purpose which will presently appear.

65 The lever 314 is operatively connected to

the lever 305 by means of a link 321 connected to the medial portion of the lever 314 and to a diagonally arranged upstanding arm 322 affixed to the lever 305 near the friction device 307. It will be observed that by virtue of the 70 springs 313 the lever 305 is vertically displaceable on the rod 309.

In the operation of the twine feeding mechanism just described, assuming that the cam 318 rotates in the direction of the arrow appearing on the gear 14 in Figure 1, when the low point or cutaway portion 318^a comes under the end of the lever 314 the spring 320 depresses said lever and brings the lever 305 downwardly substantially horizontally on the 80 rod 309 against the tension of the spring 313. This movement is immediately followed by the descent of a lever 311, and this lever striking the lower end of the rod 309 raises the inner end of the lever 172^b so that the latter 85 and the lever 305 are separated.

As the lever 305 descends under the action of the lever 314 a pull is exerted on the rod 309 by the spring 313 but as this spring is relatively light no material movement of the 90 lever 172^b is effected. The only function which results is that due to the fact that the twine is secured at one end in the machine to one of the containers the lever 305 moves, in effect, past the twine, that is, the distance between the outer end of the lever 305 and the spool is reduced, but the distance between the inner end of the lever 305 and the lever 95 172^b is increased so that in effect the twine passes from right to left as viewed in Figure 100 1 through the friction device 307, this device readily permitting the passage of twine in this direction.

Immediately after the descent of the lever 314 the lever 311 descends and strikes the nut 105 312 thereby raising the inner end of the lever 172^b through the medium of the rod 309. All the operations so far described function to 110 displace the friction device with respect to the twine, so that when the lever 305 again ascends by the lever 314 rising on the cam 318 115 an additional increment of twine will be removed from the spool and that portion of the twine between the friction device and the tying device slackened away so as to permit of sufficient slack for the next container to be 120 tied. The lever 311 follows the lever 314 in rising and again in turn permits the return of the lever 172^b to its normal position as shown in Figure 1.

After the tying operation is completed the loose string or twine shown in Figure 18 forms a loop 203 which serves later as the means for attaching a tag to the container.

This tagging apparatus is shown at G in 125 Figure 2 and is illustrated in detail in Figures 14 to 17, inclusive.

Referring to Figures 14 to 17 and in part to Figure 2 the tag delivering and attaching mechanism includes a supporting pedestal 130

205 which supports a table 206 above which is mounted a frame 207 in which a plurality of short strips or cards either of paper or cardboard or of any suitable material are 5 stacked.

The standard 205 is so disposed upon the shelf 4^a that the longitudinal axis of the table 206 will be radially arranged with respect to the axis of the turntable 110.

- 10 The mechanism which is hereinafter described as comprising the tagging apparatus operates to engage the loop 203 formed in the twine which surrounds the container, to eject a tag from the stack and to apply the loop 15 203 to said tag through an opening provided therein.

The pedestal 205 is provided with a bearing 207 which receives a revoluble shaft 208 provided with various cams for actuating the elements which perform the tagging operation.

20 The shaft 208, as will be seen upon inspection of Figure 2, is connected with the shaft 15 by two or more universal joint connections 209 and 209^a which permit of the relative 25 angular disposition of the shafts 15 and 208 due to the arrangement of the tagging mechanism on the shelf 4^a.

The table 206, as will be seen in Figures 14 and 15, is preferably cast integrally with the 30 standard or pedestal 205 but to one side of the vertical axis of said standard. The top of the table is provided with a longitudinal groove 210 in which is slidably mounted the card or tag ejecting plate 211, guide plates 35 212—212 being fixedly secured upon the upper surfaces of the table 206 at the rear of the frame 207 for retaining the ejector plate against upward displacement.

The forward or ejecting end of the plate 40 211 is reduced in thickness as at 213, to afford a shoulder 214, and this ejector plate, when moved outwardly to the position shown in Figures 2 and 15, is disposed above the loop 203 in the groove 229 as will appear later, so 45 that the card is placed to receive part of the loop to be forced through this opening in the card.

The ejector plate is reciprocated by means 50 of a cam 216 fixedly mounted upon the shaft 208 by means of a pin 208^a and said cam being held against longitudinal displacement by a collar 207^a which forms part of the bearing 207 and an end collar 208^b. The cam 216 is provided with a circumferential groove or 55 track 217 which has its major portion of the same configuration as that of an arc having the shaft 208 as its center. The groove 217 is formed with a pair of depressed portions 218—218 and another portion 219 which is 60 closer to the shaft 208 than the portion 217 of said groove so that an element travelling in the groove will move through the semicircular portion of the groove and then have its path changed by the parts 218 and 219. The high

point of the cam formed by the groove 217 is that part designated 216^a.

A bell crank lever 220 is fulcrumed on a bolt 221^a secured by a nut to the standard 205 and one arm 222 of said bell crank lever is provided with a roller 223 which operates in the groove 217, and the other arm 224 of said bell crank lever is pivotally connected by a link 225 to a lug 226 formed on the under side of the ejector plate 211. It will be obvious that as the cam 216 rotates the ejector plate 75 will be caused to reciprocate by the oscillation of the bell crank lever 220. Each time the ejector plate reciprocates forwardly or outwardly the shoulder 214 engages one of the tags from the stack supported by the frame 80 207 and conveys the tag to the point at which the loop of twine is applied.

The pedestal is provided with an integral forwardly extending support 226 which has its outer end enlarged and apertured to receive a vertical sleeve member 227 which is slidable vertically to a slight extent and is provided with a head 228 which underlies the reduced portion 213 of the ejector 85 90 211. The head 228 is provided with a transverse substantially V-shaped groove 229 which is adapted to receive the medial portion of the loop 203 as each container arrives and pauses at the tagging mechanism.

Within the sleeve 227 a needle 230 is vertically slidably mounted and, as shown in Figure 16, comprises a short rod having a notch 231 in its upper end and secured in a socket in the end of a reciprocating post 232 by means of a set screw 233, said post fitting snugly in 100 the bore of said sleeve.

The sleeve may be vertically adjusted in the support 226 and the shaft 232 extends below the lower end of said sleeve and is pivotally connected at 234 to a pair of links 235 which latter are pivotally connected at their upper ends to the arms of a yoke 236 formed on the outer end of one of the arms of a lever 237. The lever 237 is pivoted on the pedestal 205 and has an arm provided with a roller 110 115 238 which operates in the groove 217 adjacent to the roller 223 on the lever 220, as best shown in Figure 15. This cam 217 thereby also serves to elevate and depress the needle 230 to project the same past the groove 229 115 and through the opening 215.

A guide post 239 having a head 239^a is disposed adjacent to the head 228 and serves to limit the slight upward movement of the sleeve 227, and also grips the tag after the 120 ejector has receded. The needle 230 is elevated by the lever 239 against the tension of a helical spring 240 which surrounds the shaft 232, said spring being interposed between the lower end of the sleeve 227 and the 125 member 234 which connects the links 235 to the shaft 232. The spring 240 serves to yieldingly support the sleeve, so that when

the ejector again functions, the engagement thereof with the curved face 236^a of the head, will depress the latter and permit an additional increment of movement of the turntable to withdraw the tag which has been applied to the container. It will thus be seen that the sleeve has a floating position with respect to the shaft 232.

As a card or tag is projected into position 10 to receive the twine the needle 230 is elevated forcing the twine in a loop through the eye of the tag and in order that this loop may be expanded to embrace the other end of the tag I provide mechanism which is mounted above 15 the table 206 and is operated at the proper moment by the high point 216 on the cam 216.

This looping mechanism includes a carriage 241 pivotally mounted at 242 on a bracket 243 secured to the frame 207. The 20 carriage 241 oscillates about the pivot point 242 in a path adjacent to a bracket 244 having an arcuate portion 245 which is part of an arc having the pivot 242 as its center. The bracket 244 is rigidly affixed to the frame 25 207.

Motion is imparted to the carriage 241 by the lever 246 affixed to the pivot 242, link 247 connected to the lever 246 and to a lever 248, pivoted at 249 on a bracket 250, and a 30 lever 251 having a roller 251^a which rides upon the periphery of the cam 216.

The carriage comprises a relatively stationary portion 241, and a plate 242^a, which is longitudinally slidably on said carriage, 35 said plate having slots 241^b which receive each one of the guide screws 242^b.

The lower end of the carriage 241 is provided with oppositely extending lugs 252-253. Stub shafts 254 and 254^a are 40 rotably mounted in said lugs, each of said shafts having a head 255 transversely apertured to receive each a finger 256 and 256^a which fingers are held by set screws 257.

Shafts 254 and 254^a are provided with collars 258 and arms 259 and 260 are also affixed to said shafts and project toward each other and over the slidable plate 242. On the under surfaces of the arms 259 and 260 there are mounted rollers 261 and 262 formed in the 50 opposite edges of the plate 242^a so that when plate is reciprocated on the carriage 241 the fingers 256 and 256^a will be expanded. The lower end of the fingers are provided with laterally bent portions 256^b for a purpose 55 which will presently appear.

As has been previously pointed out the carriage is oscillated adjacent to the curved portion 245 of the bracket 244 and this motion by a mechanism which will now be described causes the plate 242^a to reciprocate on the carriage. The cause the reciprocation of the plate 242^a the latter is provided, on one edge, adjacent to its lower end, with a lug support 264 which carries a laterally projecting cylindrical lug 265.

The lug 265 is adapted to project into a recess or channel 266 which is cut in the inner face of the curved portion 245, the upper wall of said channel being curved in a plane parallel to that of the upper edge of the curved portion 245 and said wall having a straight diagonal portion 267 against which the lug 265 rides. 70

A spring restrained detent or pawl 268 is pivoted on a bolt or screw 269 supported by 75 the curved portion 245 and the arm of said pawl is curved to substantially the same curvature as that of said curved portion 245 and is adapted to lie in the channel 266 by the action of a contractile helical spring 270 80 fixed at one end to the bracket 244 and at the other end to a pin 270^a connected to the pawl.

The outer surface of the pawl is provided with a curved shoulder or abutment 271 spaced from the curved wall of the channel 85 266 to about the same distance as that of the diameter of the lug 265 and said lug is adapted to travel in the channel thus formed. The shoulder 271 extends to the end of the channel 266 and the wall 267 limits the inward motion of the pawl. The other end of the shoulder 271 terminates a sufficient distance from the pivot pin 269 to permit of entrance of the lug 265 into the channel 266. 90

The pawl 268 functions as a sort of a 95 switch point so that as the lug 265 slides in the channel 266 and engages the wall 267 of the lug it displaces and carries with it the plate 242^a, the pointed end of the pawl being displaced as the lug leaves the channel and 100 immediately closing by the action of the spring 270 so as to cause the lug 265, when the carriage is returned to ride on the abutment or shoulder 271. It will be obvious that as soon as the lug 265 reaches the outer end 105 of the abutment 271 the lug 265 will again enter the channel. When the lug 265 engages the wall 267 the fingers 256 and 256^a are expanded and remain expanded until the lug 265 leaves the abutment 271, whereupon the 110 fingers are returned to normal position as shown in Figure 17.

The plate 242^a is normally maintained in the position shown in Figure 17 by the provision of a helical contractile spring 273 anchored at one end to the lower screw 242^b 115 and anchored at the other end to the plate 242^a.

In order to tension the twine which lies in the groove 229 during application of the tag 120 to the twine I provide the arms 274 and 275 arranged on either side of the support 226 and adapted to oscillate vertically on the pivots 276 and 277 which in actual construction comprise a transverse shaft mounted in a bearing 278 secured below and at the rear of the table 206 on a bracket 279.

The arms 274 are provided with extensions 280 and 281, respectively, which are adapted to engage the cams 282 and 283, respectively, 125

mounted on and rotatable by the shaft 208. The arms 274 and 275 are elevated by the cams 282 and 283 against the tension of the contractile springs 284 and 285 which are secured at their lower ends to the shelf 4^a. The arms 274 and 275 are provided with notched ends 286 which engage the twine alternately and tension it during the application of the tag.

10 The mechanism for tagging operates in its proper sequence as follows: The continuous rotation of the shaft 208 and cam 216 actuates ejector 211 to bring a tag into position with its eye immediately above the needle 230, the twine being in the V-shaped groove 229.

As soon as the tag arrives in this position, and while the ejector is at rest, the needle 230 is elevated, and in thus elevating the 20 spring 240 is further compressed. The needle then passes through the eye of the tag, carrying with it the twine in the groove 229. The ejector is then withdrawn and simultaneously the needle descends leaving a loop 25 expanding upwardly from the tag which latter is held by the gripping action of the head and the step 239^a. It will be observed that the spring 240 not only serves to keep the head subject to an upward pressure, but also 30 turns the needle.

The carriage 241 then descends and as the fingers 256 and 256^a enter the loop 290 formed by the needle, these fingers are expanded, thereby expanding the loop. As the loop is 35 then adjacent the rear end of the tag, the further descent and retraction of the fingers throws the loop 290 beneath the inner end of the tag, and draws it toward the front thereof, and as the twine is tightened by an additional movement of the turntable and of the arms 274 and 275, the tag is thus connected to the container.

When the container reaches a point immediately above or adjacent to the conveyor J, 45 the twine cutting mechanism H functions to disconnect the container from the container immediately adjacent thereto.

The severing mechanism referred to comprises two relatively movable members one of 50 which is a cutting edge and the other of which is a member for bringing a twine into engagement with such cutting edge. Keeping in mind that the two adjacent containers are connected by a stretch of twine extending 55 between them reference may now be had to Figures 1 and 2, wherein this cutting mechanism is designated H.

For supporting the cutting mechanism a standard 291 is mounted on the shelf 4^a adjacent to the conveyor J and said standard is provided with a bearing 292 and a laterally extending portion 293 which also carries a bearing 294.

On a stud shaft supported by the bearing 60 292 I mount a hub 295, said hub having a

downwardly extending arm 296 connected pivotally to a link 297 and a rearwardly and upwardly extending arm 298 arranged at substantially 90 degrees with respect to the arm 296. The arm 298 has attached thereto a 70 twine engaging finger 298^a which is adapted to be depressed between two of the gripping elements on the turntable when the latter is at rest, the bearing 294 having a recess 298^b which accommodates the member 298^a when 75 depressed.

A pin 299 extends laterally from the arm 298 and engages in a yoke 300 formed on a lever 301 fulcrumed on the bearing 294. The inner end of the lever 301 carries a cutting 80 blade 302 which may be in the nature of an ordinary safety razor blade and is provided with a keen cutting edge so that relatively small amount of pressure of the blade against the twine is required to sever the same. It 85 will be obvious that when the lever 296 is rocked in the direction of the arrow in Figure 1 the member 298^a will descend and strike the twine stretched across its path. In descending the arm 298 actuates the lever 301 90 by the pin 299 to raise the blade 302 and sever the twine. It will be observed from inspection of Figure 2 that a relatively wide space exists between the member 298^a and the blade 302 and this is for the purpose 95 of preventing the knife from severing the tag loop or the tag which is attached to the container.

Motion is imparted at a proper time to the lever 296 through the link of connecting rod 297 by means of a cam 26 rotatable continuously with the shaft 11 and having its periphery in engagement with a pin 26^a on an upstanding lever 28, the latter being fulcrumed on the shaft 10 and pivotally connected at 28^a to the link 297. The connecting rod 297 extends through a suitable opening in the standard 293 as will be seen in dotted lines in Figure 2.

After the twine has been severed, and the 110 turntable starts on another increment of movement the container which has been disconnected from the other containers in the group is dropped onto the conveyor J by engagement of one of the gripping elements 115 with the cam 108 to open the gripping device. The conveyor J is driven by the pulley 303 mounted on the shaft 13.

Having thus described my invention and illustrated its use, what I claim as new and desire to secure by Letters Patent is:—

1. In an apparatus of the character described, in combination, a forming die, means for feeding blanks of material thereto, means for forming said blanks into a plurality of containers, means for applying a securing twine to said containers in succession thereby connecting the containers, and means for severing the twine between such containers. 125

2. In an apparatus of the character de- 130

- scribed, in combination, a forming die, means for feeding blanks of material thereto, means for forming said blanks into a plurality of containers, means for applying a securing 5 twine to said containers in succession thereby connecting the containers, means for applying a label or tag to the twine, and means for severing the twine between such containers.
- 10 3. In a device of the character described, in combination, means for forming a receptacle from a single piece of material, means for forming a neck on said receptacle, means for filling said receptacle and supporting the 15 same, a separate intermediate element capable of spanning the neck on said receptacle and adapted to receive loop of a flexible fastening member, and means for presenting said intermediate element in spanning 20 relation to said receptacle.
4. In a device of the character described, in combination, means for forming a receptacle from a single piece of material, means for forming a neck on said receptacle, means for filling said receptacle and supporting the same, a separate intermediate element 25 capable of spanning the neck on said receptacle and adapted to receive loop of a flexible fastening member, and means for presenting said intermediate element in spanning 30 relation to said receptacle and means on said intermediate element for transferring the convoluted fastening member to said mentioned receptacle.
- 35 5. In an apparatus of the character described, in combination, means for forming a receptacle from a single piece of material, means for grasping the receptacle to form a neck thereon and for conveying the receptacle, and means for trimming said receptacle, a separate intermediate member for spanning the receptacle adapted to receive 40 loop of a flexible fastening member, said last mentioned means including means for transferring the convoluted fastening member to said receptacle.
6. The method of packaging a commodity 45 consisting of consecutively forming from single sheets of material elongated receptacles, charging said receptacles with a predetermined quantity of said commodity, closing the top of said receptacles by means of a continuous flexible strand so that the receptacles when closed are attached to each other by 50 said strand.
7. The method of packaging a commodity 55 consisting of forming from single sheets of material elongated receptacles, charging said receptacles with a predetermined quantity of said commodity, closing the top of said receptacles by means of a continuous flexible strand, so that the receptacles when filled and closed are attached to each other by said strand and thereafter severing the strand to form individual packages.
8. The method of packaging a commodity 60 consisting of forming from single sheets of material elongated receptacles, charging said receptacles with a predetermined quantity of said commodity, closing the top of said receptacles by means of a continuous flexible strand, so that the receptacles when filled and closed are attached to each other by said strand attaching a tag to the strand between each receptacle and thereafter severing the strand 65 adjacent the tag, to form individual packages.
9. In a machine of the class described, in combination, means for forming successive sheets of material in containers, means for closing and holding the containers, an intermediate element, means for applying a series of convolutions of twine or the like to said intermediate element. 70
10. In a machine of the class described, in combination, means for forming successive sheets of material in containers, means for closing and holding the containers, an intermediate element adapted to receive a loop of twine or the like, means for presenting said intermediate element to said container for applying loops to the latter. 75
11. In a machine of the class described, in combination, means for forming successive sheets of material in containers, means for closing and holding the containers, means for receiving and supporting a loop of twine or the like, said last mentioned means being adapted to embrace the container for applying the twine thereto. 80
12. In a machine of the class described, in combination, means for forming successive sheets of material in containers, means for closing and holding the containers, means for receiving and supporting a convolution of the twine or the like and means on the twine supporting means for transferring convolutioned twine to said container. 85
13. In a machine of the class described, in combination, means for forming an elongated receptacle from a single sheet of material, means for closing and gripping the top of said receptacle, means for fastening the top of said receptacle by a continuous flexible strand while held in said gripping means, and means for attaching a tag like member to said flexible strand. 90
14. In a machine of the class described, in combination, means for forming an elongated receptacle from a single sheet of material, means for closing and gripping the top of said receptacle, means for fastening the top of the receptacle by looping a continuous flexible cord around the top of the receptacle while held by said gripping means, and means for attaching a tag like member to said flexible cord and thereafter severing the cord. 95
15. In a machine of the class described, in combination, means for forming a receptacle from a single sheet of material, a conveyor, means on said conveyor for closing and grip- 100
16. In a machine of the class described, in combination, means for forming a receptacle from a single sheet of material, a conveyor, means on said conveyor for closing and grip- 105
17. In a machine of the class described, in combination, means for forming a receptacle from a single sheet of material, a conveyor, means on said conveyor for closing and grip- 110
18. In a machine of the class described, in combination, means for forming a receptacle from a single sheet of material, a conveyor, means on said conveyor for closing and grip- 115
19. In a machine of the class described, in combination, means for forming a receptacle from a single sheet of material, a conveyor, means on said conveyor for closing and grip- 120
20. In a machine of the class described, in combination, means for forming a receptacle from a single sheet of material, a conveyor, means on said conveyor for closing and grip- 125
21. In a machine of the class described, in combination, means for forming a receptacle from a single sheet of material, a conveyor, means on said conveyor for closing and grip- 130

- ping the top of said containers, shearing means for trimming the tops of containers while in said gripping means, independent means for forming fastening loops from a 5 flexible cord, and means for transferring said loops to said containers to fasten said closed tops thereof.
16. In a machine of the class described, in combination, a bag forming means, a conveyor, gripping and closing means carried thereon, bag fastening means adjacent said conveyor, and means operating in timed relation with said conveyor to shear off the uneven tops of the bags while held by said gripping means.
17. In a bag forming and filling machine, the combination with a supporting member provided with an opening having four corner recesses, of a depressing element movable 20 through the opening to move a bag forming blank therethrough and form a partially formed bag with four definite corner folds at the mouth of the bag, a pair of gripping members positioned beneath said supporting member and opening, and provided with portions designed to engage said corner folds and effect bunch formation of each fold as the depressing element depresses the blank, and means for closing the gripping members to 30 contract the neck portion of the partially formed bag and bring said corner bunches together to form a substantially compact bunched mouth of the bag.
18. In a bag forming and filling machine, the combination with a supporting member provided with an opening having four corner recesses, of a depressing element movable 35 through the opening to move a bag forming blank therethrough and form a partially formed bag with four definite corner folds at the mouth of the bag connected by intervening substantially unfolded portions, a pair of gripping members positioned beneath said supporting member and opening, and provided with portions designed to engage said corner folds and effect bunch formation of each fold as the depressing element depresses the blank, and means for closing the gripping members to contract the neck portion of the 40 partially formed bag and bring said corner bunches together to form a substantially compact bunched mouth of the bag.
19. In a bag forming and filling machine, in combination, a supporting member provided with an opening, a hollow plunger movable through the opening to depress a bag forming blank therethrough, means for introducing loose material to within the bag, through the hollow plunger, and means for 45 engaging and contracting the neck of the bag 60 to close the mouth thereof, said means cooperating with said opening to effect the formation of a plurality of defined bunches of folds in the material forming the neck portion of the bag, connected by intervening substantially unfolded portions.
20. In a bag forming and filling machine, in combination, bag forming mechanism including means for folding a blank into an open mouth bag having a plurality of separate bunches of folds in the material forming the neck portion of the bag, means for introducing loose material into the bag, and means for contracting the neck portion of the bag to close the mouth and bring the bunches of 75 folds together.
21. In a tea bagging machine, in combination, bag forming mechanism, bag filling mechanism, means for closing the bag to enclose the tea therein, means for operatively supporting a tag in predetermined relation to the bag closed by the bag closing mechanism, and mechanism for connecting the closed bag with a tag thus supported by a substantial length of a flexible member to 80 provide the bag with a handle.
22. In a tea bagging machine, in combination, bag forming means, bag filling means, bag holding and closing means, and means for securing a handle comprising a tag and a 85 length of twine to the neck of the filled bag including means cooperating with the twine for presenting it into predetermined position with relation to a bag held by the bag holding means.
23. In a tea bagging machine, in combination, automatic bag forming means, automatic bag filling means, automatic bag holding and closing means, and mechanism for attaching to each successively formed and 90 filled bag a handle comprising a tag and a flexible connecting member of substantial length connecting the tag to the bag and correlated, and cooperating mechanism for driving all of the aforesaid mechanism in timed 95 relation to each other to produce the tea bags.
24. In an automatic tea bagging machine, in combination, mechanism for feeding bag forming material, mechanism for forming and filling successive bags, rotatable conveying means for holding the filled bags and forming constricted neck portions, and mechanism for applying a fastening device around the neck portion of each of successive bags while held by the conveyor.

In testimony whereof I have hereunto signed my name.

RALPH NELSON DOBLE.
